T. Goodrum,
Rotary Steam Valve.
N° 18,624. Patented Apr. 3, 1855.

UNITED STATES PATENT OFFICE.

THOMAS GOODRUM, OF PROVIDENCE, RHODE ISLAND.

VALVE FOR STEAM-ENGINES.

Specification of Letters Patent No. 12,624, dated April 3, 1855.

To all whom it may concern:

Be it known that I, THOMAS GOODRUM, of the city and county of Providence and State of Rhode Island, have invented an 5 Improved Induction and Eduction Valve for Steam-Engines; and I do hereby declare that the following is a full, clear, and exact description of the same, reference being had to the accompanying drawings, 10 forming part of this specification, in which—

Figure 1, is a perspective view of the valve, apart from its seat or casing. Fig. 2, is a longitudinal section of the same applied to a double cylinder steam engine. 15 Fig. 3, is a transverse section in the line x, x of Fig. 1, and Fig. 4, a transverse section in the line y, y .

Similar letters of reference indicate corresponding parts in the several figures. 20 This invention consists in a hollow cylindrical or conical valve of novel construction which receives a rotary motion corresponding with that of the engine shaft and may control the induction and eduction of steam 25 to and from one, two or more cylinders.

It also consists in an appliance to the said valve to serve the purpose of a variable cut-off, and furthermore it consists in a certain manner of arranging the said valve 30 whereby the steam passages leading from the valve to the cylinder or cylinders are shortened to the greatest possible degree.

To enable those skilled in the art to make and use my invention I will proceed to describe its construction and operation. 35

A, is the valve casing or seat consisting of a tube of about the same length as the engine cylinder, which is bored out very slightly conical in order to grind the valve 40 in tight and allow the wear to be compensated for. This casing is arranged parallel with the cylinders B, B, and bolted securely thereto and has openings a, a , and a', a' , made in it at either end to match with the 45 steam ports b, b, b', b' , at the ends of the cylinders.

C is the valve which is fitted steam tight to the casing and is bored out from end to end cylindrically or slightly conical and 50 has journals c, c' , working through stuffing boxes in the closed ends of the casing A. It is intended to have steam supplied constantly to its interior or from the induction pipe k , which enters the casing A, at one end, and for that purpose openings l, l , are 55 made in or near the end which is next the

steam pipe. It has near the ends but on opposite sides two openings d, d' , in the interior each extending nearly half around it, and being of such length as to cover 60 the openings or ports a, a' , in the casing. Opposite to the openings d, d' , are two cavities e, e' , which also extend nearly half way around the valve, corresponding exactly in that respect with the openings d, d' , and are united by a cavity f , which extends all 65 around the valve so as to communicate at all times with the eduction pipe g , which is placed at or near the middle of the length of the casing. These openings and cavities 70 in the valve only leave for its bearing surfaces the two rings h, h' , at or near the ends, which bear outside the steam ports, the divisions i, i' , and j, j , between the steam openings d, d' , and their corresponding 75 exhaust openings; and the guards m, m' , on the inner ends of the steam openings.

The cut off consists of a spindle n , with journals fitted to turn in bearings within the journals of the valve, carrying two 80 semicylindrical heads o, o' , fitting to the interior of the valve opposite to the steam openings d, d' , the said heads carrying two plates p and p' , which fit lengthwise to the openings d, d' , and which fit to the interior 85 of the valve casing B. The heads o, o' , and their plates p, p' , are capable, of contracting the openings d, d' , to any desired extent in a circular direction by being turned to a suitable position within the valve. The 90 turning of the cut off is effected by means of an endless screw q , of very quick pitch on the end of the spindle n , which projects through the journal c , of the valve, and a nut r , which fits to the said screw but is 95 prevented turning by pins s, s , or their equivalents connected with the valve. By 100 sliding this nut back or forth by means of a slider t , connected with it the endless screw is caused to turn within the nut. A graduated scale upon the slider t , will serve to adjust the cut off for any point in the stroke.

The operation of the valve and cut off will be best understood by reference to Figs. 105 3 and 4 both of which represent the valve in the same position one figure showing its relation to the ports a, a , at one end of the casing and the other figure its relation to the ports a', a' , at the opposite end at the 110 same time. The cut off is there supposed to be adjusted to cut off at about half stroke.

The right hand engine is supposed to be just passing the center the left hand one to be at half stroke. The valve makes one revolution in the direction of the arrows for 5 every revolution of the engine shaft. The bearing i , of the valve is just passing the port a , of the right hand cylinder and commencing to admit steam from the interior of the valve through the opening while the bearing g' , is just opening the opposite port a' , of the same cylinder to the exhaust. The port a , of the left hand cylinder which has been receiving steam is just being closed by the plate p , while the opposite port a' , is 10 full open to the exhaust cavity e' . The ports if properly proportioned are opened wide for receiving steam and exhausting very early in the stroke and the exhaust remains wide open till near the end of the 15 stroke. The cut off may take place very early in the stroke or steam be admitted during the full stroke by changing the position of the cut off. The variation of the cut off is illustrated by red outlines in Figs. 20 25 3 and 4 representing it set to cut off later than it does in the position represented in black. If this valve and cut off is applied to a single cylinder no change of construction is required except that only one port 30 a or a' , will be required at each end of its casing. It will be readily understood that steam might be admitted to three, four, or even more cylinders, by one valve with the cylinders arranged all round it; the only 35 change in its construction being the provision of a proper number of ports in the casing A . The valve will work otherwise than parallel with the cylinders but the arrangement in that way shortens the passages 40 and thus saves steam, and also makes the engine more compact than any other arrangement.

Instead of receiving steam through the valve and exhausting between the valve and casing steam might be admitted between 45 the valve and casing and exhausted through the valve. This would not change the character of the invention; but perhaps it would not afford quite as good facilities for the employment of a variable cut off. 50

Having thus fully described my invention I will proceed to state, what I claim and desire to secure by Letters Patent,

1. Though I do not claim to be the first inventor of rotating tubular valves for the 55 induction and eduction of the steam, I claim, the rotary tubular valve having openings and cavities arranged substantially as described to communicate with the induction and with one, two, or more openings or ports 60 a , leading to one end and a corresponding number of ports a' , leading to the opposite end of one, two, or more cylinders—whereby the same valve is enabled to control the induction and eduction of steam to both ends 65 of one, two, or more cylinders.

2. I claim the variable cut off consisting of two segments of cylinders o , and o' , and plates p , p' , applied within the tubular valve substantially as described. 70

3. I claim arranging the valve casing and the tubular valve with the axis of the valve in line with the cylinder or cylinders as herein described so as to bring the valve into a equally convenient position relatively 75 to two or more cylinders and enable the length of the passages leading from it to the cylinders to be reduced to the greatest possible degree.

THOS. GOODRUM.
